CLAIM

The ornamental design for vehicle-wheel front face, as shown and described.

DESCRIPTION

FIG. 1 is a perspective view of a vehicle-wheel front face according to my new design;

FIG. 2 is an enlarged front elevational view thereof;

FIG. 3 is an enlarged side view taken from the left side of FIG. 2, it being understood that the opposite side is a mirror image thereof; and,

FIG. 4 is a front elevational view of a second embodiment of my new design, with the only difference being a reversed curvature of the wheel spokes.

Portions of the wheel depicted in broken line are for illustrative purposes only, and form no part of the claimed design.
